DRILLING BIT

Filed Sept. 7, 1932

Fig. 1.

UNITED STATES PATENT OFFICE

FRED CLARK, OF GLADEWATER, TEXAS

DRILLING BIT

Application filed September 7, 1932. Serial No. 633,061.

The invention relates to a drilling bit and more particularly to a four-way shearing blade straight hole bit for use in oil well drilling rigs.

5 The primary object of the invention is the provision of a bit of this character, wherein there is arranged a central novelly formed pilot blade with two cutting edges, while about the same are shear blades, these being 10 of peculiar formation so as to cause a reaming action and shear or cut the soil, rock and other matter in contradistinction to a dragging operation thereon and also to force the cut material or matter toward the center 15 of the hole as the blades shear or cut during each revolution of the bit.

Another object of the invention is the provision of a bit of this character wherein the same is adaptable for use with rotary drilling rigs in digging oil and gas wells, water wells and other wells and the pitch of the shear blades being such as to deflect a water jet onto the points of said blades, the water being fed through the bit directly in front 20 of the blades thereof, the bit being of novel construction to assure a positive shearing or cutting action and a straight line boring effect without liability of dragging of the cut matter with the result that the cuttings will 25 be thoroughly broken up and the water feed through the bit dissolving such cuttings and washing the same away while the bit is in operation.

30 A further object of the invention is the provision of a bit of this character which is extremely simple in construction, thoroughly efficacious and reliable in the operation thereof, strong, durable, and inexpensive to manufacture.

35 With these and other objects in view, the invention consists in the features of construction, combination and arrangement of parts as will be hereinafter more fully described in detail, illustrated in the accompanying drawing, which discloses the preferred embodiment of the invention, and pointed out in the claims hereunto appended.

In the accompanying drawing:

40 Figure 1 is a bottom plan view of a bit constructed in accordance with the invention.

Figure 2 is a side elevation thereof.

Figure 3 is a front view of the bit.

Figure 4 is a sectional view on the line 4—4 of Figure 1 looking in the direction of the arrows.

Similar reference characters indicate corresponding parts throughout the several views in the drawing.

Referring to the drawing in detail, the bit 45 constituting the present invention comprises a body 5 in the form of a circular stock having centrally thereof a recess 6 which opens through the nipple end 7 of the same and this nipple end is in this instance internally threaded at 8 for the attachment of the stock 50 to a drill shank or rod, it being understood of course that the said stock may be otherwise attached if found desirable.

The stock 5 has formed at its outer or working end the diametrically opposed tangentially arranged outer cutting blades 9, these being extended beyond the outer surface of the stock longitudinally thereof for a major portion of its length while formed at substantially right angles to these blades 9 55 are the radially disposed outwardly extending follower blades 10, these having the beveled side shear or cutting edges 11 and likewise the blades 9 have the beveled shear or cutting edges 12, thus by this disposition of these blades 9 and 10 the same present a four-bladed shear cutter or bit. The blades 9 protrude beyond the outer end of the stock 5 and are formed with beveled reversely angled 60 edges tips 13, while the blades 10 are terminated at their outer ends inwardly with respect to the tips 13 and have their outer surfaces rounded at 14 for the tapered formation thereof in the direction of the tips 13. It will be apparent that the blades 12 lie tangentially to the stock 5 while the blades 10 are disposed radially with respect to said stock and these blades 10 on rotation of the stock follow the blades 9 for shear cutting 65 action corresponding to the said blades 9.

Arranged diametrically opposite each other and at the outer portion of the stock 5 midway between the blades 9 is a pair of shear blades 15, these at their outer side edges terminating flush with the outer surface of 70

the stock and the same are disposed at a tangent to the axis of the stock and at an angle to the blades 9, the tips 16 of these blades 15 having reversely angled edges 17 and function in the working of the bit for reaming action.

At the outer end of the stock 5 centrally thereof is a double bevel edged pilot blade 18, the beveled edges 19 being offset in parallel relation to each other of the pilot blade 18.

Leading from the recess 6 in the stock 5 immediately forwardly of the blades 9, 15 and 18 are water passages 20 which serve to render a water jet onto these blades for the cleaning thereof of the cuttings and also for the dissolving of the latter and the washing away of the matter or material when the bit is active in the drilling of a well either oil, gas or water. The pitch or disposition of the blades 9 and 15 serves to force the cuttings to the center of said bit and the said blades 15 by the set or pitch thereof are at the proper angle for shearing or cutting the material from the side and bottom of the bore rather than gouging or dragging action thereon. These blades 15 are placed one on each side of the pilot blade 18 and at an angle of approximately twenty degrees to thirty degrees from the parallel with the inner edges 20 slightly shorter than the outer or shearing edges thereof, causing the tips to slope or slant inwardly at an angle of approximately twenty-two degrees with the result that the outer blades 9 and 10 cut or shear in advance 35 of the same with a tendency to hold the bit to a perpendicular downward course and preventing the hole from angling off at a tangent.

It will be obvious that the passages 20 next to the blades 9 are larger than those next to the pilot blade 18 and are so disposed or pitched as to direct the water jet to the points and cutting edges of these blades. It also will be noted that the water passages 20 are 45 located in front of the shear blades 15 and that said shear blades 9, 11 and 15, as well as the pilot blade 18, are thinner at the tips or points and edges than elsewhere and thicker almost immediately in the direction of the 50 stock 5 of the bit.

The blades 9 are set at an angle of approximately fifteen degrees to twenty degrees bisecting a line drawn parallel with the pilot blade and these are the longer of the remaining blades of the bit.

The bit in its operation is designed to shear the material away rather than gouge or drag it and to maintain or keep a straighter perpendicular hole throughout its operation.

The pilot blade 18 by reason of the medial bight 21 therein effects a slight propeller-like twist causing each cutting edge 19 to slant or thrust forward and this pilot blade is considerably shorter than the shear blades causing it to cut behind all of the other blades

and thus tending to again hold the bit in a straight downward line, the water passages 20 next to this blade being in front of the cutting edges 19 and so placed and pitched as to direct the water jet to the cutting edges and 70 points of the pilot blade.

What is claimed is:

1. A bit of the character described comprising a body forming a circular stock having a central recess and a nipple end through 75 which the recess opens, threads internally of the nipple for attachment of a drill shank therewith, diametrically opposed tangentially arranged outer cutting blades on said stock and extended beyond the outer face longitudinally thereof for a major portion of its length, radially disposed outwardly extending follower blades on the stock at substantially right angles to the first named blades and having beveled shear edges, said first 80 named blades having beveled shear edges, beveled reversely angled edged tips formed on the first named blades and protruded beyond the ends of the stock opposite the nipple, the second named blades being terminated inwardly with respect to the tips and having their outer surfaces rounded and tapering in the direction of the tips, a pair of shear blades located on the stock midway between the first named blades and terminating 85 flush with the outer face of said stock and disposed at a tangent to the axis thereof, and a pilot blade centrally on the outer end of the stock and having double beveled edges, one beveled edge of the latter being offset in parallel relation to the other.

2. A bit of the character described comprising a body forming a circular stock having a central recess and a nipple end through 105 which the recess opens, threads internally of the nipple for attachment of a drill shank therewith, diametrically opposed tangentially arranged outer cutting blades on said stock and extended beyond the outer face longitudinally thereof for a major portion of its length, radially disposed outwardly extending follower blades on the stock at substantially right angles to the first named blades and having beveled shear edges, said first 110 named blades having beveled shear edges, beveled reversely angled edged tips formed on the first named blades and protruded beyond the ends of the stock opposite the nipple, the second named blades being terminated inwardly with respect to the tips and having their outer surfaces rounded and tapering in the direction of the tips, a pair of shear blades located on the stock midway between the first named blades and terminating 115 flush with the outer face of said stock and disposed at a tangent to the axis thereof, and a pilot blade centrally on the outer end of the stock and having double beveled edges, one beveled edge of the latter being offset in parallel relation to the other, the stock 120

having water passages leading from the recess therein to points inwardly with respect to the first and second named blades and opening through the outer end of the stock.

- 5 3. A bit of the character described comprising a body forming a circular stock having a central recess and a nipple end through which the recess opens, threads internally of the nipple for attachment of a drill shank
- 10 therewith, diametrically opposed tangentially arranged outer cutting blades on said stock and extended beyond the outer face longitudinally thereof for a major portion of its length, radially disposed outwardly extending
- 15 follower blades on the stock at substantially right angles to the first named blades and having beveled shear edges, said first named blades having beveled shear edges, beveled reversely angled edged tips formed
- 20 on the first named blades and protruded beyond the ends of the stock opposite the nipple, the second named blades being terminated inwardly with respect to the tips and having their outer surfaces rounded and tapering in the direction of the tips, a pair of shear blades located on the stock midway between the first named blades and terminating flush with the outer face of said stock and disposed at a tangent to the axis thereof, and
- 25 a pilot blade centrally on the outer end of the stock and having double beveled edges, one beveled edge of the latter being offset in parallel relation to the other, the stock having water passages leading from the recess there-
- 30 in to points inwardly with respect to the first and second named blades and opening through the outer end of the stock, certain of the passages being of larger extent than the remaining passages and disposed at a
- 35 pitch to direct water jet to the points and cutting edges of said blades.
- 40

In testimony whereof I affix my signature.
FRED CLARK.
